[57] CLAIM

The ornamental design for a barbell plate, as shown and described.

DESCRIPTION

FIG. 1 is a front elevational view showing my new design for a barbell plate;

FIG. 2 is a side elevational view of the barbell plate shown in FIG. 1;

FIG. 3 is a front perspective view of the barbell plate shown in FIG. 1;

FIG. 4 is a front elevational view of a second embodiment of a barbell plate showing my new design;

FIG. 5 is an end elevational view of the barbell plate shown in FIG. 4; and

FIG. 6 is a front perspective view of the barbell plate shown in FIG. 4.

FIG. 7 is a front elevational view of a third embodiment of a barbell plate showing my new design;

FIG. 8 is a side elevational view of the barbell plate shown in FIG. 7; and,

FIG. 9 is an elevational perspective view of the barbell plate shown in FIG. 7.

The side of the barbell plate opposite to that shown in FIG. 1 is the mirror image thereof; the side of the barbell plate opposite to that shown in FIG. 4 is the mirror image thereof; and the side of the barbell plate opposite to that shown in FIG. 7 is the mirror image thereof.
